UNITED STATES PATENT OFFICE.

JOHN B. HADAWAY, OF SWAMPSOFT, MASSACHUSETTS, ASSIGNOR TO UNITED SHOE MACHINERY CORPORATION, OF PATERSON, NEW JERSEY, A CORPORATION OF NEW JERSEY.

ART OF HEEL ATTACHING.

Application filed January 7, 1925. Serial No. 1,109.

To all whom it may concern:

Be it known that I, JOHN B. HADAWAY, a citizen of the United States, residing at Swampscott, in the county of Essex and 5 Commonwealth of Massachusetts, have invented certain Improvements in the Art of Heel Attaching, of which the following description, in connection with the accompanying drawings, is a specification, like 10 reference characters on the drawings indicating like parts in the several figures.

This invention relates to the art of heel attaching. In one aspect, the invention aims to provide a method of producing a tight 15 joint between the base and top sections of a two-section heel. In another aspect, the invention consists in an improved two-section heel having tightly jointed base and top sections.

According to the invention a method is provided which overcomes a difficulty sometimes met in the attachment of vulcanized heel top sections such, for example, as rubber half heels. This difficulty arises from 20 shrinkage of the rubber or other composition of which the vulcanized heel top section is made, the shrinkage manifesting itself in the form of a depression or space at the edge of the attaching face of the heel section.

This shrinkage cannot be accurately predicted nor exactly controlled because it varies with the composition of the compound of which the heel section is made, the shape 25 of the heel section, and the characteristics of the nail anchoring insert, when one is used. When such a heel section is attached to a heel base presenting a flat surface an opening or crack remains at the line of junction of the top section and base. This 30 shrinkage effect is particularly conspicuous in some types of that class of rubber heels which have vulcanized into their attaching faces a stiffening or nail anchoring element of material which is harder than the body 35 of the heel and is less in area than the attaching face of the heel. In respect to such rubber top sections the shrinkage of the rubber sometimes produces a decided offset or depression in the breast end of the attaching face of the vulcanized heel section, and when the heel is attached a crack remains 40 across the breast which it is impossible to close by any of the methods of heel attaching heretofore known.

In carrying out the method of the present invention a protuberant portion, of sufficient height to fill any space or depression in the attaching face of the vulcanized top section which may be created by shrinkage, is formed upon the outer face of a heel base 45 section, being so located as to fill any depression or space which may exist at the edge of the heel when the two sections are combined and attached to a shoe. In this manner the effect of shrinkage of the vulcanized top section is nullified in so far as the existence of any crack or opening at the joint between the two sections of the heel after attachment to the shoe is concerned. It thus becomes a comparatively simple matter to overcome the detrimental effect of the 50 variable shrinkage factor and to produce invariably a tight edge joint. The two heel sections may be combined, in register with each other, and attached as a unit to a shoe, or the base section may be attached to the shoe and the top section then be registered with the base and attached; the result in either case being that the two sections are attached, in register with each other, to the 55 shoe.

From another viewpoint a composite heel is provided which includes a top section of vulcanized, resilient material with a shrunk-breast end, in combination with a base section having upon the breast end of its outer face a protuberant portion of sufficient height to fill the space at the breast end of the attaching face of the top section created by shrinkage. The heel is devoid of 60 cracks or openings at its breast when attached to a shoe, a tight joint between the two heel sections always being insured.

Other features and advantages of the invention will be understood and appreciated 65 from reading the following detailed description of a preferred manner of practising the method and one embodiment of the heel itself, in connection with the accompanying drawings, in which

Fig. 1 is a perspective view of a vulcanized rubber heel top section, viewed from the attaching face side and showing a space or depression created at the breast end of the attaching face by shrinkage;

Fig. 2 is a perspective view of a heel base section prepared in accordance with the present invention; and

Fig. 3 illustrates a composite two-section heel in which the top and base sections are combined in register with each other and attached to a shoe.

In carrying out the method of the present invention a heel base section 10 is prepared by forming upon its outer face at its breast end a protuberant portion 12 which is so located as to fill any depression or space, such as that shown at 14, at the breast end of the attaching face of the heel top section 16 with which the base section is to be combined. The protuberant portion 12 may be formed by molding the heel base section 10 under pressure, or by any other practicable, convenient method and will preferably be of a height sufficient to fill the space 14 created by the uncertain shrinkage of the vulcanized top section material, regardless of variations in the degree of such shrinkage as it may occur in different specimens of top sections. This is practicable and produces entirely satisfactory results because the top section 16 is made of rubber or similar, rather soft, material and is capable of yielding sufficiently to accommodate the protuberant portion 12 even if the said portion is higher than may be necessary to close the space 14 in the particular top section 16 with which the base is to be combined.

The particular heel top section 16 herein illustrated is made of vulcanized rubber or equivalent, resilient material and has vulcanized into its attaching face an element 18 of material which is harder than the body of the heel and less in area than the attaching face of the heel. The element 18 may be made of wood or any other material suitable for anchoring the attaching nails, one of which is shown at 20, and aiding in the production of a permanently tight joint around the edges of the heel. The breast end of the top section 16 herein shown is shrunken to such an extent that the depression or space 14, in front of the element 18, is quite apparent and would create an unsightly crack or opening if the said top section were attached to an unprepared base having a flat outer face.

The base 10, prepared as above described, and the top section 16 may be combined, in register with each other, and attached as a unit to the shoe 22, as shown in Fig. 3; or the prepared base section may first be attached to the shoe and the top section then be registered with the base and attached, the result in either case being that the two sections are attached, in register with each other, to the shoe.

When the two heel sections are registered with each other, as shown, and nailed down tightly upon the shoe the joint 24, at the breast of the heel, is tightly and permanently closed and devoid of cracks or openings, a very desirable condition which it has heretofore not been possible to secure with certainty.

Having described the invention, what is claimed as new and desired to be secured by Letters Patent is:—

1. That method of producing a tight edge joint between a heel top section made of material subject to shrinkage and a heel base section which consists in forming upon the outer face of the heel base section a protuberant portion of sufficient height to fill the space in the attaching face of the top section created by shrinkage, and attaching the top and base sections, in register with each other, to a shoe.

2. That method of producing a tight breast edge joint between a vulcanized heel top section and a base section which consists in forming upon the outer face of the heel base section at its breast end a protuberant portion of sufficient height to fill the space at the breast end of the attaching face of the top section created by shrinkage, applying the top and base sections, in register with each other, to a shoe, and attaching both sections to the shoe.

3. That method of producing a tight breast edge joint between a vulcanized heel top section and a base section which consists in forming upon the outer face of the heel base section at its breast end a protuberant portion of sufficient height to fill any space at the breast end of the attaching face of the top section created by shrinkage, combining the top and base sections, in register with each other, applying the combined top and base sections as a unit to a shoe, and attaching both sections to the shoe.

4. A composite heel comprising a top section of vulcanized, resilient material with a shrunken breast end, and a base section having upon the breast end of its outer face a protuberant portion of sufficient height to fill the space at the breast end of the attaching face of the top section created by shrinkage, said top and base sections being attached together in register with each other to provide a heel devoid of cracks or openings at its breast.

In testimony whereof I have signed my name to this specification.

JOHN B. HADAWAY.
